UNITED STATES PATENT OFFICE.

STEPHEN A. KROM, OF BIRMINGHAM, ALABAMA.

SINTER-PAN.

1,391,124.

Specification of Letters Patent. Patented Sept. 20, 1921.

Application filed July 3, 1920. Serial No. 393,989.

To all whom it may concern:

Be it known that I, STEPHEN A. KROM, a citizen of the United States of America, residing at Birmingham, in the county of Jefferson and State of Alabama, have invented 5 certain new and useful Improvements in Sinter-Pans, of which the following is a specification.

My invention relates to a sinter pan especially designed for the quick and easy stripping of the sinter from the grate without requiring manual labor or expensive construction or manipulation of the pan.

Heretofore it has been sought to strip the sinter from the grates by hand labor which is tedious and expensive and to facilitate the removal of the sinter it has been proposed to swivel the sinter pan so that it can be inverted.

According to my present invention I propose to mount the hopper and grate supporting sections of the sinter pan on fixed supports and provide a separate retaining wall to hold the material to be sintered on the grate, and this wall I propose to shift laterally causing it to drag or strip the sinter from the grate and in doing so to break up the sinter so that it will fall freely from the movable top wall when the latter clears the grate.

It is a further object to provide the movable wall with a bottom cutting ring which will take the wear incident to stripping the sinter from the grates and which can be replaced from time to time.

A further object of my invention is to mount the movable wall of the pan on rollers and provide tracks therefor, a pusher ram being connected to the wall to move it back and forth from operating to dumping position.

My invention comprises the novel details of construction and arrangements of parts, which in their preferred embodiment only are illustrated in the accompanying drawings which form a part of this specification, and in which:—

Figure 1 is a side elevation of the sinter pan, the dotted lines showing the movable retaining wall shifted to dumping position.

Fig. 2 is a plan view of Fig. 1; and

Fig. 3 is a partial sectional view taken on the line 3—3 of Fig. 1.

Similar reference numerals refer to similar parts throughout the drawings.

As illustrated, I show a sintering pan com-

prising an annular top ring 1 and an annular grate ring 2 cast with an internal lug 3 upon which the members 4 of the grate are supported. The grate ring has cast integral with it a downwardly converging apron 5 which forms the top portion of the hopper. The hopper is formed by a metallic casing 6 which at its upper end is seated in the apron 5 and attached thereto in any suitable manner. At its bottom the hopper is provided with a connection to the air suction pipe 7, which in turn is connected to any suction engine or suitable exhaust. The type of grate may be of any suitable character and may be integral or in units. The grate ring 3 is connected on each side by brackets 8 which are in turn connected to a pair of parallel I-beams 9 which extend substantially beyond the hopper ring on each side and are supported at intervals by cross beams 10. The cross beams are arranged adjacent to the hopper so as to support the load thereon intermediate the beams 9 by other brackets 8. A track rail 11 is mounted on top of each I-beam 9 and extends from end to end thereof. The top ring 1 is cast with trunnions 12 upon which are mounted wheels 13 which ride the tracks 11. These wheels are diametrically oppositely disposed. I attach to the top ring by means of the bracket 14 and H-axle 15, and on this axle are bolted end trunnions on which are mounted wheels 16 similar to 13. A geared pusher or ram 17 is connected to the center of this axle 15 and its teeth mesh with the teeth of a pinion gear 18 which in turn is driven by a gear train 19 that in turn is driven by the electric motor 20 or any other equivalent prime mover. The rear end of the pusher is guided between the rolls 21 below and roll 22 above, these being all mounted in a frame 23 that is set on the I-beams 10.

The top ring 1 is formed as a casting having an inwardly sloping upper annular face 24 terminating at a straight vertical annular wall 25 which continues to the base flange 26 of the ring and comes flush with the inner wall of the grate ring. To this flange 26 is bolted a steel cutting ring 27 having a downwardly beveled cutting edge 28. The trunnion wheels 13 and 16 support this edge 28 just clear of contact with the grate ring 2. The top ring 1 is strengthened by external webs 29.

The apparatus having been constructed

and assembled as described, its operation is as follows. The material to be sintered is delivered by any suitable mechanism or appliance onto the grate 4 of the sintering pan and the latter is filled usually level with the top of ring 1, whereupon the blast is put on and the sintering operation commences. When this operation is completed and it is desired to remove the sinter from the pan, the motor is started and the pusher ram drives the top ring 1 with its cutting ring 27 ahead of it, forcing it to strip with it the sinter from the top surface of the grate, and in doing this the sinter is broken up and loosened so that as the top ring moves to dotted line position, which it reaches at the end of the pusher stroke, all of the sinter which has been drawn off with it from the grate will fall freely away from the top ring into a hopper (not shown), or any suitable collecting point. The motor is reversed, the top ring is drawn back to position above the grate and the operation is repeated, it being noted that the bodily movement of the top ring will most effectively strip the grate without requiring any hand labor and the sinter will all drop off from the top ring without requiring that it shall be loaded or broken, which is the general present practice.

I prefer the annular construction of the sinter pan as by this means the cutting ring 27 can be shifted from time to time until its whole edge is worn, it being apparent that the maximum wear thereon comes on the portion in line with the pusher.

This ring is made of hardened steel so as to be durable and as it takes practically all of the wear, the ring 1 does not require replacement. My invention contemplates the supporting of the movable ring on any type of guide or support and moving it in any manner or by any means suitable, so long as the pan retaining wall is utilized as a movable stripper for the grate.

This invention is not intended to be restricted in scope to the specific embodiments shown, but contemplates such modifications

as come within the spirit and scope of the claims.

Having thus described my invention, what I claim as new and desire to secure by Letters Patent, is:—

1. A sinter pan comprising a grate supporting section, and a movable charge retaining section above the grate adapted to be shifted laterally to clear the grate section.

2. The combination with a sinter pan having a grate therein, of a movable wall for retaining the charge on the grate, tracks to support said wall, and means to shift said wall on said tracks from position above the grate.

3. A sinter pan comprising a fixed grate and a support therefor, a detached marginal wall provided at its bottom with a cutting edge, and guides upon which said wall is movable to cause said edge to strip the sintered charge from the grate.

4. The combination with a sinter pan having a lower grate supporting portion, and means to rigidly support the same, of a charge retaining wall for the pan separate from the bottom and comprising a bottom cutting edge lying close to the top surface level of the grate, wheel supports for said retaining wall, a track on which said wheel supports travel, and a power driven pusher ram to shift said wall of the pan on its roller supports from position above the grate to position clear of the grate to thereby strip the sinter from the grate, substantially as described.

5. A sinter pan having its charge retaining wall movable, a detachable hardened cutting attachment at the bottom edge of said wall, the cutting attachment and wall being shaped to permit the attachment to be shifted to present different faces thereof to the work, and means to shift said wall relatively to the pan to cause it and its cutting attachment to strip the sinter from the pan.

In testimony whereof I affix my signature.

STEPHEN A. KROM.
